UNITED STATES PATENT OFFICE.

FRANCIS FISHER, OF GREELEY, NEBRASKA.

WAGON-BOX.

SPECIFICATION forming part of Letters Patent No. 717,979, dated January 6, 1903.

Application filed February 21, 1902. Serial No. 95,090. (No model.)

To all whom it may concern:

Be it known that I, FRANCIS FISHER, a citizen of the United States, residing at Greeley, in the county of Greeley and State of Nebraska, have invented a new and useful Wagon-Box, of which the following is a specification.

My invention is an improved wagon-box; and it consists in the peculiar construction and combination of devices hereinafter fully set forth and claimed.

My present invention is an improvement on the wagon-box for which Letters Patent of the United States No. 359,436 were granted to me March 15, 1887.

One object of my present invention is to effect improvements in the construction of the hinges which I employ to connect the upper and lower sections of the wagon-box together.

A further object of my invention is to provide means for vertically adjusting the hinges with reference to the lower section of the wagon-box to close the cracks between the upper and lower sections of the wagon-box to prevent the loss of grain.

A further object of my invention is to effect improvements in the construction of the hinge leaves and pintles whereby the upper section of the box is rendered detachable at will from the lower section thereof and whereby the upper section when adjusted to an angle with relation to the lower section is prevented from becoming detached therefrom.

In the accompanying drawings, Figure 1 is a side elevation of the rear portion of one side of a wagon-box embodying my improvements, showing one of the hinges which connect the upper and lower sections together and also showing the locking-bolt. Fig. 2 is a vertical sectional view of the same, taken on a plane intersecting the center of one of the hinges. Fig. 3 is a detail perspective view of one leaf of the hinges.

In the embodiment of my invention I provide a plurality of hinges 1, which connect the lower and upper sections 2 3 of the wagon-box together, so that the upper section may be turned outwardly and disposed at substantially right angles to the lower section, as shown in dotted lines in Fig. 2, whereby the upper section may be turned to a vertical position, as shown in full lines in Fig. 2, and whereby said upper section may be detached

from the lower section by first moving the same endwise a sufficient distance to disengage the pintles of the hinges, as indicated in dotted lines in Fig. 1.

The upper leaf 4 of each hinge is provided with double straps 5, which bear on the outer and inner sides of the upper box-section 3, the latter being suitably mortised or rabbeted in its lower edge, as at 6, to receive the lower portion 7 of the upper hinge-leaf, which connects the straps 5 together. The said straps of the upper hinge-leaf are secured to the upper section 3 of the wagon-box by a bolt 8, as shown in Fig. 2, and the said upper leaf of the hinge is provided on its under side with an ear 9, which is disposed to bear against the outer side of the lower section 2 of the wagon-box and is provided with a pintle 10. The said pintle is provided near its outer end with a locking-stud 11, which is disposed at right angles thereto and parallel with the lower side of the upper hinge-leaf. Said upper hinge-leaf is provided on its outer strap near its upper end with a pair of outstanding lugs 12, between which is pivoted the upper end of a brace 13 by a pin or bolt 14. A spring 15, which is preferably of the form here shown, is secured to the outer strap 8 of the upper hinge-leaf by the bolt 8 and bears against the outer side of the brace 13, near the upper pivoted end thereof, and normally maintains the brace in the position shown in full lines in Fig. 2, so that the inner or lower end of the brace bears at all times against the outer side of the lower hinge-leaf.

The lower hinge-leaf 16 is also provided with double straps 17, which bear, respectively, against the outer and the inner sides of the lower section 2 of the wagon-box and are provided with vertical adjusting-slots 18. The upper portion 19 of the lower hinge-leaf, which connects the upper ends of the double straps 17 together, is rabbeted in the upper edge of the lower section of the wagon-box, as at 20. The said lower leaf of the hinge is secured to the lower section of the wagon-box by a bolt 21, which engages the adjusting-slots 18, and the latter, as will be understood, enable said lower hinge-leaf to be vertically adjusted on the lower wagon-box section, so that a tight joint is effected and maintained between the lower and upper wagon-

box sections to prevent the loss of grain from the wagon-box. The lower leaf of the hinge is provided on its outer strap, at the lower end thereof, with an outstanding lug 22. On 5 the inner side of the said lug is formed a recess 23, which is adapted to be engaged by the lower end of the brace 3 when the upper box-section is turned to the position indicated in dotted lines in Fig. 2, said brace, as will 10 be understood, serving to secure said upper section in such position.

A bearing-plate 24 of suitable construction is secured by bolts, screws, or other devices to the outer side of the lower box-section below the center of each of the hinges. Adjusting-screws 25 engage threaded openings in the said bearing-plates, and the upper ends of said adjusting-screws are swiveled in sockets, with which the lugs 22 are provided. 15 Hence the hinges may be adjusted vertically by turning said adjusting-screws. The lower ends of the adjusting-screws are here shown as formed with wings or thumb-heads 26 to adapt them to be readily turned by hand.

20 The length of the pintle 10 of each pin is such that when the leaves of the hinge are joined together, as shown in full lines in Fig. 1, the locking-stud 11 will bear on the outer side of the lug 27, formed on the upper portion of the lower leaf. Said lug has a bore 28 to receive the pintle, and a groove 29 on one side of and which communicates with said bore to adapt the stud to move through the said groove when the upper hinge-leaf is being connected to the lower hinge-leaf. The 25 groove 29 is so located that the locking-stud 11 registers therewith when the upper hinge-leaf is in a vertical position. Hence the upper section of the wagon-box may be drawn longitudinally to cause the stud 11 to move through the groove 29 while the pintle 10 is being withdrawn from the bore 28 to disengage the upper hinge-leaf from the lower hinge-leaf, as shown in dotted lines in Fig. 30 1, in order to disconnect the upper box-section from the lower box-section. When the hinge-leaves are connected together, as shown in full lines in Fig. 1, the locking-stud 11 is on one side of the lower hinge-leaf, as here-

inbefore stated, and is out of engagement 50 with the groove 29, and hence the upper box-section may be lowered to the position shown in dotted lines in Fig. 2. The said locking-stud 11 operates to prevent the upper hinge-leaf from being disconnected from the lower 55 hinge-leaf, excepting when said hinge-leaves are disposed in the same plane. The upper section of the wagon-box is secured against longitudinal movement on the lower section thereof when in the vertical position shown 60 in full lines in Figs. 1 and 2 by a bolt 30.

Having thus described my invention, I claim—

1. In combination with the upper and lower sections of a wagon-box, a connecting-hinge, 65 one of the leaves of which is provided with a socket, and a spring-pressed brace pivotally connected to the other leaf and adapted to engage said socket, when said leaves are disposed at an angle with relation to each other, 70 substantially as described.

2. A hinge to connect the lower and upper sections of a wagon-box together and comprising two pivotally-connected leaves, a spring-pressed brace pivotally connected to one of 75 the leaves, and coacting devices on the other leaf and the free end of the brace, to lock said brace to the last-mentioned leaf when the leaves are disposed at an angle with relation to each other, substantially as described. 80

3. In combination with the lower and upper sections of a wagon-box, a hinge connecting said sections together and having a brace pivotally connected to one of its leaves, the other leaf having a lug formed with a recess on its 85 inner side to receive the free end of the brace when the leaves are disposed at an angle, and an adjusting-screw having a fixed support and engaging the said lug, substantially as described. 90

In testimony that I claim the foregoing as my own I have hereto affixed my signature in the presence of two witnesses.

FRANCIS FISHER.
